UNITED STATES PATENT OFFICE.

JOHN FEKETTE, OF ELIZABETH, NEW JERSEY.

LOCK.

1,090,700.

Specification of Letters Patent. Patented Mar. 17, 1914.

Application filed April 21, 1913. Serial No. 762,671.

To all whom it may concern:

Be it known that I, JOHN FEKETTE, a subject of the King of Hungary, residing at Elizabeth, in the county of Union and State 5 of New Jersey, have invented certain new and useful Improvements in Locks, of which the following is a specification, reference being had therein to the accompanying drawing.

10 This invention relates to locks, and more particularly to that class known as pad locks.

The primary object of my invention is to furnish a lock of the above type with simple and effective means, as hereinafter set forth, for holding the shackle of the lock in a manner that it is unnecessary to resort to the use of tumblers, wards and other key actuated elements.

15 Another object of this invention is to provide a barrel lock having a longitudinally disposed shackle that can be easily and quickly released, whereby the lock can be used in connection with large staples and 20 hasps.

A further object of this invention is to provide a lock consisting of comparatively few parts that are inexpensive to manufacture, durable and highly efficient for the 25 purposes for which they are intended.

With the above and other objects in view the invention resides in the novel construction, combination and arrangement of parts to be hereinafter specifically described and 30 then claimed.

Reference will now be had to the drawing wherein:

Figure 1 is a longitudinal sectional view of the lock showing the shackle in a locked 40 position, Fig. 2 is a similar view showing the shackle released, and Fig. 3 is a cross sectional view of the lock.

A lock in accordance with this invention comprises a barrel 1 that has one end there- 45 of provided with a thick wall 2 and with oppositely disposed lugs 3. Pivotally mounted between the lugs 3 by a rivet 4 or other pivotal means is a longitudinally disposed curved shackle 5 that has a hook- 50 shaped end 6 adapted to extend into a cut away portion 7 provided therefor in the end of the barrel. Slidably mounted in the barrel is a cylindrical bolt 8 and said bolt has a transverse slot 9 providing clearance 55 for a transverse pin 10, carried by the barrel, said pin limiting the movement of the

bolt 8 within the barrel. The outer end of the bolt is provided with a recess 11 to receive the hook-shaped end 6 of the shackle, and the inner end of said bolt is reduced, 60 as at 12 and provided with a stem 13 that extends into a longitudinal opening 14 provided therefor in the end wall 2 of the barrel. The reduced end of the bolt is encircled by a coiled compression spring 15, 65 which is interposed between the bolt and the end wall 2.

The stem 13 has a longitudinal bore 16 and the walls of said bore are screw threaded to receive a screw 17 having a head or handle 18, said screw serving as a key to the lock. By screwing the screw 17 into the stem 13, the screw and stem can be pulled outwardly, the spring 15 placed under tension, and the bolt 8 shifted longitudinally of 75 the barrel, whereby the hook-shaped end of the shackle will be released, as shown in Fig. 2, thereby permitting of the shackle being swung to an open position.

A lock in accordance with this invention 80 is made of a strong and durable metal, and while in the drawing there is illustrated a preferred embodiment of the invention it is to be understood that the structural elements are susceptible to such variations and 85 modifications as fall within the scope of the appended claims.

What I claim is:

1. A lock comprising a barrel having one end wall of greater thickness than the other, 90 said thinner end wall cut away adjacent the periphery to provide an opening, a curved shackle pivotally connected at one terminus to said thicker end and provided with a hook adapted to extend in said opening, a 95 cylindrical bolt slidably mounted in said barrel and having one end adjacent the periphery recessed for the reception of said hook, said bolt having a reduced end provided with a stem projecting from the thickened end of the barrel, a coiled compression spring mounted upon the reduced end of the bolt, and a screw adapted to be mounted in said stem to facilitate shifting the bolt to release the shackle. 100

2. A lock comprising a barrel having one end wall of greater thickness than the other, 105 said thinner end wall cut away to provide an opening, a curved shackle pivotally connected at a terminus to said thicker end and provided with a hook adapted to extend in said opening, a cylindrical bolt slidably

mounted in said barrel and having one end adjacent the periphery recessed for the reception of said hook, said bolt having a reduced end provided with a stem projecting from the thickened end of the barrel, a coiled compression spring mounted upon the reduced end of the bolt, a screw adapted to be mounted in said stem to facilitate shifting the bolt to release the shackle, and

means for limiting the movement in either 10 direction of said bolt.

In testimony whereof I affix my signature in the presence of two witnesses.

JOHN FEKETTE.

Witnesses:

JOE PEUVEHER,
SANDOR FODOR.
